UNITED STATES PATENT OFFICE.

JOHN S. FREESE, OF BROOKLYN, NEW YORK.

BUTTON-HOLE SEWING-MACHINE.

SPECIFICATION forming part of Letters Patent No. 403,424, dated May 14, 1889.

Application filed March 19, 1888. Serial No. 267,730. (No model.)

To all whom it may concern:

Be it known that I, JOHN S. FREESE, a citizen of the United States, and a resident of Brooklyn, in the county of Kings and State 5 of New York, have invented certain new and useful Improvements in Button-Hole Sewing-Machines, of which the following is a specification.

My invention relates, especially, to that 10 class of button-holesewing-machines for which I filed an application May 11, 1886, Serial No. 201,802; and it consists of certain novel features of construction, hereinafter described, for stitching across both ends of the button- 15 hole with an eye at one end and a bar at the other without turning the fabric.

In the accompanying drawings, Figure 1 represents a partial side view and partial vertical longitudinal section of a sewing-machine 20 embodying my invention. Fig. 2 represents a partial top or plan view and partial horizontal section thereof. Fig. 2* represents a detail view of parts. Fig. 3 represents a partial inverted plan view and partial horizontal 25 section of the machine, the plane of section being indicated by the line $x-x$, Fig. 1. Fig. 4 represents a partial end view and partial cross-section thereof. Fig. 5 represents the button-hole stitches. Figs. 6, 7, and 8 illustrate a modification of the invention, Fig. 8 being a cross-section on line $y-y$, Fig. 6, omitting some of the parts.

Similar letters of reference indicate corresponding parts.

Referring to Figs. 1 to 4, inclusive, the letter A indicates the stationary machine-arm; B, a vibrating arm forming the needle-bar carrier pivoted to the stationary arm, and C an eccentric on the driving-shaft D, connect- 35 ed to the vibrating arm by means of a pit- man, C', in the usual manner. The driving- shaft D has its bearings in suitable portions of the machine-arm and carries a looper, D', which co-operates with the needle to form the 40 button-hole stitch.

The letter F indicates the cloth-plate of the machine, having two opposite edges fitted in guideways F', which are secured to a feed- bar, G, extending under the cloth-plate across 45 the machine, the feed-bar being in turn fitted in guideways G' on the lower forward portion, A', of the machine-arm to move in a line

opposite to the line of said ways of the cloth- plate, which line of the bar is the line of the feed. Upon the cloth-plate F is arranged the 55 clamp F² and its concomitants for holding the fabric during the sewing operation.

The letter H indicates the feed-wheel, which is mounted horizontally on a suitable shaft depending from a bracket, A², of the ma- 60 chine-arm, and in the upper surface of which is a cam-groove, H', Fig. 2, for operating a feed-lever, G², while in the lower surface thereof is a second cam-groove, H², Fig. 3, for operating an adjusting-lever, I, hereinafter 65 more fully described.

The feed-lever G² has its fulcrum in a pivot, G³, which is adjustably or otherwise secured in a standard, G⁴, rising from the base A³ of the machine, and at each end of said lever is 70 a longitudinal slot, G⁵, by one of which it engages a stud, J', of a bell-crank, J, Fig. 2*, connecting with the feed-bar G, while by the other slot it engages a stud, G⁶, fitted in the cam-groove H' of the feed-wheel, the stud 75 last named being also fitted in a slot, G⁸, formed in the bracket A² radially to the feed- wheel.

The letter J² indicates a crank-operating rod extending under the feed-wheel H, one 80 end of which rod has a stud, J³, Fig. 3, fitted in a concentric groove, H³, in the lower surface of the feed-wheel and the other end of which has a slot, J⁴, Fig. 2*, into which is fitted a stud, J⁵, of the bell-crank J, this stud 85 being on one arm of the bell-crank and the stud J' being on the other arm thereof, while at the junction of said arms is a pivot, J⁶, whereby the bell-crank is united to the feed- bar G. Said slot J⁴ of the operating-rod is 90 parallel to the line of feed, and to accommodate the slot the rod is bent laterally, as shown, its bent and slotted portion resting on the lower forward portion, A', of the machine- arm, while the bell-crank J in turn rests on 95 the rod between it and the feed-bar G, as more clearly shown in Fig. 4. The crank-oper- ating rod J² also has a longitudinal slot, J⁷, Fig. 3, whereby it straddles the shaft of the feed-wheel H, thus maintaining a radial po- 100 sition thereto, and the concentric groove H³ of the feed-wheel receiving the stud J³ of said rod has two serpentine cams, H⁴ H⁵, approxi- mately opposite to each other.

The letter N indicates a cloth-plate-operating wheel which is mounted horizontally above the driving-shaft D on a staff, N', rising from a block, N², Fig. 1, which is arranged to slide on said shaft, it being held against rotating by a cheek-piece, N³, Figs. 3 and 4, rising from the base A³ of the machine. In the upper surface of said operating-wheel N is a cam-groove, N⁴, into which is fitted a stud, N⁵, of a rod, N⁶, having a longitudinal slot, N⁷, whereby it straddles the wheel-staff N' and also a second stud, N⁸, fitted into a slot, F³, of the cloth-plate, this slot being parallel to the line of feed. The lower surface of the operating-wheel N is toothed to gear with a correspondingly-toothed driving-wheel, N⁹, which is mounted on the driving-shaft D to slide thereon as well as to share the motion of the shaft.

On the bottom of the sliding block N² is an extension, N¹⁰, having its end bent upward and bifurcated to straddle the hub of the driving-wheel N⁹ for confining said wheel between it and said block, thereby causing the wheel to slide and fro with the block.

The adjusting-lever I, Fig. 3, before referred to, has its fulcrum in a post, I', rising from the base A³ of the machine, and said lever has a stud, I², at one end fitted into the cam-groove H² of the feed-wheel, while it is connected at the other end to the sliding block N², as by a pivot, I³, of said extension or any other suitable portion of the block.

The letter O, Fig. 3, indicates a feed-dog lever, and O' a detent-lever, both engaging frictionally with a concentric groove, O², in the lower surface of the feed-wheel H under the impulse of a suitable spring, the feed-dog also engaging with a cam, O³, of the driving-shaft for operating the feed-wheel in a well-known manner.

In the periphery of the feed-wheel H are ratchet-teeth P, to engage with a pawl, P', which is held in peripheral contact with said wheel by the action of a spring, P², said pawl being pivoted to one end of a lever, P³, Fig. 3, which has its fulcrum in the feed-wheel shaft and engages at the other end with a cam, P⁴, for operating the lever together with the pawl, said cam being in this example formed by a bevel on the periphery of the lower portion of the pitman C', and a stop, P⁵, being adjustably secured to an adjacent portion of the machine-arm A for arresting the lever, the operation of said cam P⁴ being to oscillate said lever in each descent of the pitman, and thereby advance the pawl for its engagement with successive teeth of the feed-wheel. Said teeth P of the feed-wheel are arranged in groups or series opposite to each other and in such relation to the serpentine cams H⁴ H⁵ that the feed-pawl P' is in engagement with the teeth during the operation of said cams to reciprocate the crank-operating rod J², the effect being to impart a positive motion to the feed-wheel during said operation.

The periphery of the feed-wheel H has also

a notch or depression, Q, Fig. 2, to receive one end of a stop-lever, Q', at which end said lever is shaped to engage a stop-pin, Q², on one end of a clutch-lever, Q³, the latter having also a second pin, Q⁴, to engage grooved collar Q⁵, which is mounted on the driving-shaft D to slide thereon, and to which is secured one end of a feather-key, Q⁶, Fig. 1, of the driving-shaft, the other or outer end of which key has a lug or clutch, Q⁷, adapted to enter a radial notch, Q⁸, in the hub of a loose pulley, D², on the driving-shaft, for imparting motion to said shaft from the pulley.

The stop-lever Q' and the clutch-lever Q³ have their fulcra in posts rising from the base A³ of the machine, and said levers are connected together by a spring, Q⁹, which has a tendency to hold the stop-lever in peripheral contact with the feed-wheel and to draw the end of the clutch-lever having the stop-pin Q² toward the stop-lever.

The operation of my machine is as follows: In the intermittent rotary motion of the feed-wheel H the feed-lever G² is oscillated by the action of the cam-groove H² of said wheel, and the feed-bar G and the cloth-plate F and its ways F' are moved uniformly in reverse parallel directions by the action of the feed-lever through the medium of the bell-crank J, while during both of said feed motions the cloth-plate is reciprocated in a line opposite to the line of feed by the action of the operating-wheel N through its cam-groove N⁴ and the rod N⁶ for bringing the needle alternately in and out of the fabric containing the button-hole to be sewed. The length of said reverse feed motions of the cloth-plate F determines the length of the button-hole, and during the intervals between said motions, or when the ends of the button-hole have been reached, the cloth-plate is reciprocated in the line of the feed by the action of the serpentine cams H⁴ H⁵ of the feed-wheel on the feed-bar G, while said plate is also moved, irrespective of its reciprocal motion, opposite to the line of feed in one direction during one interval and in the other direction during the other interval between said feed motions by the action of the cam-groove H² of the feed-wheel on the operating-wheel N and its rod for bringing the needle from side to side of the button-hole, so that by said reciprocal motion of the cloth-plate and its simultaneous adjustment sidewise to the button-hole the needle is permitted to stitch across both ends of the button-hole without the necessity of turning the fabric for that purpose. In said adjustment of the cloth-plate, together with its operating mechanism, it is moved reciprocally in one direction, with the effect of forming a round eye, T, at one end of the button-hole, and uniformly in the other direction, with the effect of forming a straight bar, T', at the other end of the button-hole, as indicated in Fig. 5. Said action of the serpentine cams H⁴ H⁵ of the feed-wheel on the feed-bar G is effected through the crank-rod J² and the bell-

crank J, said rod being reciprocated by the action of the cams on the stud J³ of the rod, and the bell-crank being oscillated on the stud J' by the action of the rod through its slot J⁴ on 5 the stud J⁵ of the crank, while the feed-bar in turn is reciprocated by the action of the pivot J⁶, whereby the crank is connected to said bar. In the feed motions of the cloth-plate the stud J⁵ of the bell-crank travels in 10 the slot J⁴ of the crank-rod, and the crank forms a connecting-link between the feed-bar G and the feed-lever. The action of the cam-groove H² of the feed-wheel on the operating-wheel N is effected through the adjusting-lever I, which is oscillated on its pivot I', while the sliding block or bearing N² is moved lengthwise of the driving-shaft D by said lever, carrying with it the operating-wheel and its connections. 15

20 The ratchet-teeth P are in fixed relation to the serpentine cams H⁴H⁵ of the feed-wheel—that is to say, said teeth are in engagement with the pawl P', and the wheel is advanced by the action of the pawl through the pawl-lever P³ during the reciprocal action of the cams on the crank-rod J², and since the motion of the wheel is thus rendered positive during these periods the regularity of the stitches across the end of the button-hole is 25 insured.

When in the motion of the feed-wheel H its peripheral notch Q is brought opposite the stop-lever Q', the end of said lever drops into the notch and releases the stop-pin Q² of the 30 clutch-lever Q³, thus permitting the latter to follow the action of the spring Q⁹, the effect of which is to automatically shift the clutch-lever in a direction to draw the sliding collar Q⁵ inward upon the driving-shaft and bring 35 the clutch Q⁷ of the feather-key on said shaft out of engagement with the pulley D², so that the shaft ceases to derive motion from the pulley and the operation of the machine is arrested. Said arrest in the operation of the 40 machine takes place whenever a button-hole has been completed, and in order to again put the machine in operation the clutch-lever Q³ is adjusted by hand to re-engage the clutch Q⁷ with the pulley D² and is retained in that 45 position until the notch Q of the feed-wheel has cleared the end of the stop-lever Q', as shown in Fig. 2.

In the modification shown in Figs. 6, 7, and 8 the crank-rod J² is reciprocated from the 50 rod N⁶ of the cloth-plate-operating mechanism, as follows: In the crank-rod J² is a hole or socket, S, and in the operating-rod N⁶ is a corresponding socket, S', each of which sockets is adapted to engage with one end of a 55 connected lever, S², extending transversely to said rods, it having its fulcrum in a swivel-joint, S³, on a post rising from the base of the machine. Said transverse lever S² engages on one side of its joint with one end of a 60 shifting lever, S⁴, which has its fulcrum in a pivot secured to the machine-arm A, and the other end of which engages with a cam- 65

groove, S⁵, Fig. 7, in the periphery of the feed-wheel H in such a manner that in the reverse feed motions of the cloth-plate F, and 70 while the sides of the button-hole are being formed, the shifting-lever is in a position to hold the connecting-lever out of engagement with the operating-rod N⁶, thus leaving the crank-rod J² stationary, while during the intervals of said feed motions, and while the 75 ends of the button-hole are being formed, the shifting lever takes a position to hold the connecting-lever in engagement with both the operating-rod and the crank-rod, so that the motion of the operating-rod is transmitted to the crank-rod by the connecting-lever. The crank-rod J² rests on a bracket, S⁶, secured to the base of the machine, and in said bracket is a hole or socket, S⁷, which coincides with 80 that of the crank-rod and receives the proper end of the connecting-lever S², while the crank-rod is inoperative for locking said rod during that period.

The shifting lever S⁴ may be elastic to 90 spring the ends of the connecting-lever S² into the holes or sockets of the respective rods.

What I claim as new, and desire to secure by Letters Patent, is—

1. In a button-hole sewing-machine, the combination, with the stitch-forming mechanism and cloth-plate, of a feed-bar mounted upon said plate, a feed-wheel having in one face a plain feed-cam, H', connected with the feed-bar, and having in the other face serpentine cam H⁴H⁵ and an adjusting-cam, H², the former also connected with the feed-bar by means substantially such as herein described, an operating-wheel having a cam, N⁴, 105 connected with the cloth-plate, an adjusting-lever, I, connecting the operating-wheel with said adjusting-cam H² of the feed-wheel, and a driving-shaft connected with the feed-wheel and operating-wheel, the whole constructed 110 and arranged substantially as herein described, for the purpose set forth.

2. In a button-hole sewing-machine, the combination, with the cloth-clamp and stitch-forming mechanism, of a feed-bar, a feed-lever, a feed-wheel having a cam for operating the feed-lever, a driving-shaft connected with the feed-wheel for operating the same, a crank-rod having a slot parallel to the feed-bar, a bell-crank having a pivot connecting it to the feed-bar, and two studs fitted, respectively, into a slot at one end of the feed-lever and into said slot of the crank-rod for reciprocating the feed-bar, and a means for reciprocating the crank-rod, substantially as and for 125 the purpose described.

3. In a button-hole sewing-machine, the combination, with the cloth-clamp and stitch-forming mechanism, of a feed-bar, a feed-lever, a crank-rod having a slot parallel to the 130 feed-bar, a bell-crank having a pivot connecting it to the feed-bar, and two studs fitted, respectively, into a slot at one end of a feed-lever and into said slot of the crank-rod for

reciprocating the feed-bar, a feed-wheel having a cam for operating the feed-lever, a driving-shaft connected with the feed-wheel for operating the same, and cams in said wheel 5 for reciprocating the crank-rod, substantially as and for the purpose described.

4. In a button-hole sewing-machine, the combination of a feed-wheel having a peripheral notch, a driving-shaft connected with the 10 feed-wheel for operating the same, a loose pulley on said shaft, a clutch adapted to engage said pulley for connecting it with the shaft, a stop-lever having one end arranged

in peripheral contact with the feed-wheel and constructed to drop into said notch of the 15 wheel for releasing the driving-shaft from the pulley, a clutch-lever having a stop-pin for engaging said end of the stop-lever, and a spring connecting the stop-lever and clutch-lever, substantially as and for the purpose 20 described.

JOHN S. FREESE.
